Brutocao, Toronto, Ontario, Canada

Application December 7, 1944, Serial No. 567,097

8 Claims. (Cl. 47—55)

1

This invention relates to flower picks.

In the florist business the use of stiff picks for setting up various floral arrangements is a common practice which facilitates work of this kind. Up to the present time two general types of picks have been known. A wooden pick used in conjunction with a length of wire which is fastened to the floral pieces by winding the wire. A more recent type of construction is a metal pick which may be channelled for strength and which includes projecting tabs that can be clinched over the stems, etc., of the flowers. This latter type of construction however required the use of a special instrument for clinching purposes in order to obtain substantial grip on the stems.

Both of these structures have obvious disadvantages. In the first case the winding of wire constitutes a substantial amount of work and therefore the process is slow. In the second case the necessity for using a machine to effect clinching requires a specialized operation while it is also necessarily slow because of the fact that the instrument has to be employed each time. The present invention clearly avoids the disadvantages of the prior art and provides a simple flower pick which in use will have all the advantages of these other structures. It is therefore an object of the present invention to provide a simple metal flower pick which may be quickly applied to stems and the like of flowers and will secure them in firm gripping engagement merely by simple use of the thumb and fingers of the user.

A further object of the invention is to provide a pick of this kind which is particularly simple in construction and which therefore can be manufactured at a comparatively low cost.

A further object of the invention is to provide a pick of this kind which when attached to the stems of flowers and the like will provide a substantial reinforcement.

With these and other objects in view, the invention generally comprises a pick formed from a short length of sheet metal channelled for strength to form a shank and having adjacent its upper end an integral strip of metal projecting laterally on each side of the shank and at an incline to the vertical axis of the shank, the said strip preferably including a toothed portion and being capable of spiral winding around the stem of flowers and the like.

The invention will be more clearly understood by reference to the following detailed specification taken in conjunction with the accompanying drawings.

Fig. 1 is a pictorial illustration of a short 55 and below the upper extremities of the pick.

2

stemmed flower with a pick of the present invention attached thereto.

Fig. 2 is an enlarged partial perspective illustration of the flower pick.

Fig. 3 is an enlarged longitudinal section taken substantially along the line 3—3 of Fig. 1.

Fig. 4 is an enlarged transverse section taken substantially along the line 4—4 of Fig. 1.

Fig. 5 is a transverse section taken through 10 an alternative form of binding strip to show the use of teeth along the upper edge instead of the lower edge as shown in Fig. 2.

Figs. 6 and 7 represent transverse sections taken through picks to illustrate a varied channelled 15 formation that may be used.

Referring to the drawings A indicates the flower pick as a whole which is preferably produced from metal, and formed with a shank 10 which is preferably of thin metal channelled for reinforcing purposes. This may be channelled 20 in any suitable way and may have a channel formation such as shown in Figs. 6 and 7. The lower end of the shank is generally pointed as at 11 while the upper end has integrally attached thereto a strip of metal 12 which is disposed at an incline to the longitudinal axis of the shank 10. The strip 12 is preferably toothed as indicated at 13 having a toothed portion offset from the plane of the strip 12 so as to project at a suitable angle thereto. The teeth preferably 25 project from the lower edge of the strip 12 but may be formed to project from the upper edge thereof such as shown in Fig. 5 and may also project at right angles to strip 12 if desired.

The strip 12 projects on each side of the shank 30 10 in the arms 14 and 15, the arm 15 preferably being shorter than the arm 14 although the arm 15 might, if desired, be of substantially the same length.

The pick thus formed provides a readily handled article which does not require any special mechanism or the like to apply it. It is only necessary for instance to dispose a stem of a flower or the like 16 along the channelled portion of the shank 10 and by twisting the binding 40 strip 12 around the stem, the strip spirals around the stem both above and below the point of attachment of this strip to the shank 10 and due to the natural spiraling of this strip it will be readily turned into firm engagement with the

50 stem wherein the toothed portions act as a gripping means preventing axial movement of the pick relatively to the stem 10 and firmly holding the pick to the stem. Moreover, it should be noted that the stem is firmly held both above

Consequently it will be understood that by merely applying a pick to a stem and quickly twisting the arms 14 and 15 of the strip 12 the pick is quickly and firmly attached and the strip assumes a spiral formation immediately upon twisting due to its inclination to the longitudinal axis of the pick.

What we claim as our invention is:

1. In a flower pick of the class having a shank adapted to align with and embrace the stem of a flower; a binding strip connected to said shank adjacent one of its extremities, the longitudinal axis of said binding strip extending at an incline to the longitudinal axis of said shank and being windable to spirally surround the stem of a flower aligned with said shank and firmly retain it in fixed relation thereto.
2. In a flower pick of the class having a shank adapted to align with and embrace the stem of a flower; a binding strip integrally connected to said shank adjacent one of its extremities, the longitudinal axis of said binding strip extending at an incline to the longitudinal axis of said shank and being windable to spirally surround the stem of a flower aligned with said shank and retain it in fixed relation thereto, said binding strip having stem engaging means projecting therefrom designed to engage in the stem of a flower when said strip is wound around said stem.
3. In a flower pick of the class having a shank adapted to align with and embrace the stem of a flower; a binding strip integrally connected to said shank adjacent one of its extremities, the longitudinal axis of said binding strip extending at an incline to the longitudinal axis of said shank and being windable to spirally surround the stem of a flower aligned with said shank and firmly retain it in fixed relation thereto, said binding strip having a plurality of teeth extending from at least one longitudinal edge thereof designed to extend into the stem of a flower when said strip is wound around said stem.
4. In a flower pick of the class having a shank adapted to align with and embrace the stem of a flower; a binding strip connected to said shank at one of its extremities, the longitudinal axis of said binding strip extending at an incline to the longitudinal axis of said shank and being windable to spirally surround the stem of a flower aligned with said shank and retain it in fixed relation thereto.
5. In a flower pick of the class having a shank adapted to align with and embrace the stem of a flower; a binding strip connected to said shank at one of its extremities, the longitudinal axis of said binding strip extending at an incline to the longitudinal axis of said shank and being windable to spirally surround the stem of a flower aligned with said shank and retain it in fixed relation thereto, said binding strip having a plurality of teeth extending from at least one longitudinal edge thereof designed to extend into the stem of a flower when said strip is wound around said stem.
6. In a flower pick of the class having a shank adapted to align with and embrace the stem of a flower; a binding strip connected to said shank at one of its extremities, the longitudinal axis

of said binding strip extending at an incline to the longitudinal axis of said shank and being windable to spirally surround the stem of a flower aligned with said shank and retain it in fixed relation thereto, said binding strip extending on either side of said shank, one portion of said binding strip being adapted to extend from one side of said shank beyond the end of said shank adjacent to which said strip is connected, said above mentioned portion being longer than the remaining portion of said binding strip that extends from the opposite side of said shank.

7. In a flower pick of the class having a shank adapted to align with and embrace the stem of a flower; a binding strip integrally connected to said shank adjacent one of its extremities, the longitudinal axis of said binding strip extending at an incline to the longitudinal axis of said shank and being windable to spirally surround the stem of a flower aligned with said shank and retain it in fixed relation thereto, said binding strip extending on either side of said shank, one portion of said binding strip being adapted to extend from one side of said shank beyond the end of said shank adjacent to which said strip is connected, said above mentioned portion being longer than the remaining portion of said binding strip that extends from the opposite side of said shank, said binding strip having a plurality of teeth extending from at least one longitudinal edge thereof designed to extend into the stem of a flower when said strip is wound around said stem.

8. In a flower pick of the class having a shank adapted to align with and embrace the stem of a flower; a binding strip connected to said shank at one of its extremities, the longitudinal axis of said binding strip extending at an incline to the longitudinal axis of said shank and being windable to spirally surround the stem of a flower aligned with said shank and retain it in fixed relation thereto, said inclined binding strip extending on either side of said shank, one portion of said binding strip being adapted to extend from a side of said shank beyond the end of said shank to which said strip is connected, said above mentioned portion being longer than the remaining portion of said binding strip that extends from the opposite side of said shank.
